JACQUARD FEEDING MECHANISM

Elbridge R. Holmes, Worcester, Mass., assignor to
Crompton & Knowles Loom Works, Worcester,
Mass., a corporation of Massachusetts

Application December 21, 1936, Serial No. 116,973

5 Claims. (Cl. 139—329)

This invention relates to Jacquard mechanisms as used in looms for weaving figured fabrics, and relates more particularly to devices for intermittently advancing the cylinder by which the pattern cards are presented to the Jacquard needles. These cylinders are commonly square in cross section and are shifted alternately toward and away from the needles. During the outward shifting movement, the cylinder is given a quarter turn to advance the next pattern card to operative position, and for this purpose studs are commonly provided in one end of the cylinder, which studs successively engage a coacting pull-over or feed pawl during successive outward movements of the cylinder.

It is the object of my invention to improve the construction of the feed device in such manner that the cylinder may be at all times under positive control, and that free and too rapid forward movement of the cylinder will be prevented.

My invention further relates to arrangements and combinations of parts which will be herein-after described and more particularly pointed out in the appended claims.

A preferred form of the invention is shown in the drawing, in which

Fig. 1 is a side elevation of parts of a Jacquard mechanism, including the cylinder and feeding devices;

Figs. 2 and 3 are side elevations similar to Fig. 1 but showing the parts in different successive positions; and

Fig. 4 is a partial plan view, looking in the direction of the arrow 4 in Fig. 1.

Referring to the drawing, I have shown a Jacquard cylinder 10 rotatable on a bearing shaft or gudgeons 11 and adapted to present successive pattern cards C to the Jacquard needles 12 which are mounted in the usual manner in a needle board 14. The usual operating mechanism (not shown) is provided for shifting the cylinder 10 away from the needles 12 in the direction of the arrow a, and for thereafter giving the cylinder an operative return movement.

The cylinder 10 is commonly of square cross section and is preferably provided with studs 15, 15^a, 15^b, and 15^c, one in each corner of the cylinder, at one end thereof. A presser foot or spring hammer 18 is mounted above the cylinder studs 50 and normally yieldingly engages the two upper studs and maintains the cylinder in one of its operative positions, as shown in Fig. 1. The hammer 18 is mounted to shift laterally with the cylinder 10, as the cylinder is moved toward or away from the needles 12.

The construction thus far described is the usual commercial structure and in itself forms no part of my present invention, which relates to an improved device for intermittently advancing the cylinder 10 anti-clockwise or in the direction of the arrow b in Figs. 1 to 3.

It has been customary to provide a pull-over or feed pawl in the form of a simple hook which would ride over the outermost upper stud, as 15^a when the cylinder moved toward the needles 12, but which would be engaged by the stud 15^a as the cylinder was thereafter moved away from the needles. The pull-over pawl would then advance the cylinder in an anti-clockwise direction one-fourth of a revolution during each outward or inoperative movement of the cylinder.

During the first half of this outward movement, the hammer 18 would be raised by the stud 15^a against the force of gravity or spring pressure which held the hammer in engagement with the studs. After the stud 15^a passed its uppermost position, as shown in Fig. 2, the pressure of the hammer 18, would complete the angular advance of the cylinder at a rapidly accelerating speed until the hammer engaged the stud 15^b, when the angular movement would be suddenly stopped.

This sudden stopping of the cylinder has been found objectionable, as a chain of pattern cards may be of considerable weight and this weight is sustained entirely by the cords which connect adjacent cards. The rapid acceleration and subsequent sudden stopping of the cylinder weakens the cord suspension and shortens the useful life of the pattern card chain.

In order to prevent this undesirable acceleration and sudden stopping of the cylinder, I have provided the improved pull-over or feed pawl shown in the drawing, which comprises a pawl 20 having a latch 21 pivoted on a stud 22 in the outer end thereof. An offset lug 23 (Fig. 4) of the latch 21 overlies the pawl 20 and limits downward movement of the latch, while permitting free upward swinging movement thereof. The pawl 20 is mounted on a fixed pivot 25 and normally rests on a stop pin 26.

As the pattern cylinder 10 moves toward the position shown in Fig. 1 and in a direction opposite to the arrow a in Fig. 1, the latch 21 is lifted idly above the stud 15^a until it clears the stud, 50 whereupon it drops to the position shown in Fig. 1. As the pattern cylinder is thereafter shifted to the right in Fig. 1, the uppermost outer stud 15^a is engaged by the latch 21, and the cylinder 10 is rotated to the position shown in Fig. 2, at the 55

same time lifting the hammer 18 as previously described.

A shoulder 27 is provided on the pawl 20, which shoulder is spaced from the vertical face of the latch 21 sufficiently to admit the stud 15^a but with only slight clearance. As the cylinder 10 continues to move outward, the turning movement is continued as indicated in Fig. 3, but rapid acceleration of the cylinder by the hammer 18 is prevented by engagement of the stud 15^a with the shoulder 27. The stud 15^a does not clear the shoulder 27 until the angular movement of the cylinder has been so far completed that no objectionable acceleration or over-abrupt stopping will thereafter occur. The angular motion of the cylinder is thus positively controlled and the strains on the pattern card chain are substantially reduced or eliminated.

The stop pin 26 holds the pawl 21 in such a position that the cylinder studs are clear of the pawl when the cylinder is in operative position.

Having thus described my invention and the advantages thereof, I do not wish to be limited to the details herein disclosed, otherwise than as set forth in the claims, but what I claim is:—

1. In a Jacquard mechanism, a pattern card cylinder, yielding means to hold said cylinder in operative position, means to give said cylinder periodical angular advance movements, said latter means having an associated device effective to prevent free angular advance movement of said cylinder by said yielding means during a major part of each advance movement.

2. In a Jacquard mechanism, a pattern card cylinder, yielding means to hold said cylinder in operative position, means to give said cylinder periodical angular advance movements, and means to prevent free angular forward movement of said cylinder by said yielding means during a major part of each advance movement, but said latter means releasing said cylinder for control by said yielding means as said advance movement is nearly completed.

3. In a Jacquard mechanism having a pattern card cylinder with end studs, a feeding device for said cylinder comprising a pull-over pawl and a latch pivotally mounted on said pawl for free upward swinging movement from operative position, said pawl and latch having stud-engaging surfaces spaced apart to receive one of said cylinder studs with slight lateral clearance and thereby preventing free angular movement of said cylinder relative to said pawl and latch during a major part of each advance movement of said cylinder. 5

4. In a Jacquard mechanism having a pattern card cylinder with end studs, a feeding device for said cylinder comprising a pull-over pawl, a latch pivotally mounted on said pawl for free upward swinging movement from operative position, and means to limit downward movement of said latch relative to said pawl, said pawl and latch having stud-engaging surfaces spaced apart 20 to receive one of said cylinder studs with slight lateral clearance and thereby preventing free angular movement of said cylinder relative to said pawl and latch during a major part of each advance movement of said cylinder. 25

5. In a Jacquard mechanism having a pattern card cylinder with end studs, a feeding device for said cylinder comprising a pull-over pawl and a latch pivotally mounted on said pawl for free upward swinging movement from operative position, said pawl and latch having stud-engaging surfaces spaced apart to receive one of said cylinder studs with slight lateral clearance and thereby preventing free angular movement of said cylinder relative to said pawl and latch during a 30 major part of each advance movement of said cylinder, and a stop to hold said pawl with its stud-engaging surface above the normal position of the upper cylinder studs during final inward operative movement of said cylinder. 35 40
